UNITED STATES PATENT OFFICE.

CONDY C. GALLAGHER, OF PHILADELPHIA, PENNSYLVANIA.

PROPHYLACTIC DEVICE.

1,260,180.

Specification of Letters Patent. Patented Mar. 19, 1918.

Application filed May 6, 1916. Serial No. 95,776.

To all whom it may concern:

Be it known that I, CONDY C. GALLAGHER, a citizen of the United States, and a resident of Manayunk, Philadelphia, in the county 5 of Philadelphia, State of Pennsylvania, have invented certain new and useful Improvements in Prophylactic Devices, of which the following is a specification, reference being had to the accompanying 10 drawings.

My invention relates particularly to such dispensing devices as may be employed in connection with a toilet flush to introduce prophylactic agents into the water used in 15 flushing the bowl.

It is well known that disease is readily contracted by the common use, especially in public places, of toilet devices, and that typhoid fever germs are particularly susceptible 20 of being carried by the water lying in such devices.

The principal objects of my invention are, to prevent the spread of disease in this manner by providing mechanism which may be 25 coöperatively connected with the flushing apparatus to automatically antisepsicize the water employed for flushing purposes.

Other objects of my invention are, to provide simple and efficient mechanism that 30 will perform the function desired, without care or attention other than maintaining it charged with the antisepsicizing agent.

My invention further comprehends means 35 for effecting the discharge of a predetermined quantity of the antisepsicizing agent into the water in the flushing tank each time the flushing mechanism is actuated, irrespective of the length of time said flushing mechanism is held open by the user.

Specifically stated, the form of my invention as hereinafter described comprises 40 mechanism adapted to be attached to a flush tank, and has a reservoir in which the antisepsicizing agent may be stored, a valve having means connected with the flushing apparatus arranged to release a predetermined 45 quantity of said agent from said reservoir when said flushing apparatus is actuated to flush the bowl, and means for arresting said released antisepsicizing agent until the water in said tank reaches a predetermined level.

My invention also includes all of the vari-

ous novel features of construction and arrangement as hereinafter more definitely 55 specified.

In the accompanying drawings, Figure 1 is a sectional front elevational view of a toilet flush tank, having a convenient form of my invention attached thereto and shown 60 in section for convenience of illustration; Fig. 2 is a plan view of the attachment shown in Fig. 1, showing only a fragment of the tank; Fig. 3 is a vertical longitudinal view of a modification of my invention; and 65 Fig. 4 is a sectional view of a modification of the valve for controlling the conveyer tube.

In said figures, the toilet flush tank 1, which is of a well-known construction, comprises the inlet pipe 2 and the outlet pipe 3, and has the rock-shaft 5 provided with the rocker arms 6 and 7, respectively connected by the rod 8 with the operating knob 9, and by the rod 10 with the rod 11 of the 70 float valve 12, which is seated on the outlet valve 13.

The prophylactic attachment to which my invention specifically relates comprises the bracket 15 arranged to be attached to the 75 side of the tank 1, and has the flange 16 forming a cup arranged to receive the cylindrical receptacle 17, preferably formed of glass, and having the spiral tubular coil 19 for holding and conveying spherical anti- 80 septicizing pills 20.

The pills 20 are fed into the tank 1, one by one, by valve mechanism comprising the valve casing 21, having the inlet 22 connected with the lower end of the coil 19, as shown 85 in Fig. 1, and controlled by the slide valve 23 which has the aperture 24 arranged to register with said inlet 22 when moved toward the left in Fig. 1, in opposition to the spring 25 by the rocking of the rock-shaft 90 5, which carries the rocker arm 26 connected by the rod 27 with said valve 23.

The movement of the valve 23 to open the inlet 22 permits the pill 20 adjacent thereto to drop through the aperture 29 into the 100 conveyer tube 30 which extends into the tank 1, and which has the clack-valve 31 at its discharge end arranged to arrest the pills 20 which are delivered thereto by the slide valve 23.

The clack-valve 31 is arranged to be 105

opened to discharge the arrested pill 20 into the cage or basket 32 which is carried by said conveyer tube 30, by means controlled by the rise and fall of the water 33.

5 in the tank 1, and comprising the bifurcated lever 34 pivoted to the tube 30 upon trunnions 35 and having prongs 36 extending loosely through apertures 37 in said valve, as best shown in Fig. 2.

10 Said lever 34 is connected by the rod 38 with the float 39, which is arranged to rise and fall within a limited range with the rise and fall of the water 33, it being obvious that when the water falls said float 15 also falls to the position indicated by dot and dash lines, thus carrying the lever 34 and valve 31 to the position similarly indicated to open said valve 31 and thereby discharge the pill 20 into the cage 32 after the 20 water has fallen below the lower end of said cage.

In order to feed the pills 20 one or more at a time, the valve 23 carries a finger 40 extending upwardly through the slot 41 in the 25 valve casing 21 and turned parallel with the axis of said valve and arranged to be thrust through the alined apertures 42 in the outlet 22, which are disposed in such position that said finger 40 will be thrust 30 between the pills 20 and hold those pills above said finger from entering the valve when opened.

It will be obvious that when the knob 9 is manually forced downward, the shaft 5 is 35 rocked to shift the valve 23 into open position, whereupon the pill 20 adjacent thereto will be released to drop into the conveyer 30 and is arrested by the clack-valve 31 until the water 33 has dropped below the lower 40 end of the cage 32, when the weight of the float 39 opens said clack-valve 31 and permits the pill 20 to drop into the cage 32 to antisepicize the water 33 when it again rises, as shown in Fig. 1.

45 The form of my invention shown in Fig. 3 is adapted to dispense a liquid antiseptic into the tank 45, and comprises the reservoir 46 having its funnel-shaped bottom 47 provided with the outlet 48 controlled by the 50 valve 49 having the aperture 50 arranged to register with said outlet and having the aperture 51 in the opposite wall disposed in staggered relation and arranged to register with the aperture 52 in the conveyer tube 55 55 53. Said valve is spring-actuated in the same manner as the valve shown in Fig. 1.

The conveyer tube 55 shown in Fig. 4 is provided with the spring valve 56 arranged to control the outlet 57, and is actuated by 60 the float 59 to which it is connected by the rod 60.

I do not desire to limit my invention to the precise details of construction and arrangement as herein shown, as it is obvious 65 that various modifications may be made

therein without departing from the essential features of my invention as defined in the appended claims.

Having thus described my invention, I claim:

70 1. A prophylactic device adapted to be used in connection with a toilet flush tank having flushing apparatus, comprising a reservoir for an antiseptic agent, means arranged to release a predetermined quantity 75 of said agent when said apparatus is actuated, and means independent of said releasing means actuated by the water in said tank arranged to arrest said agent thus released and discharge it into said tank when the water falls to a predetermined level.

2. A prophylactic device adapted to be connected with a toilet flush tank having flushing apparatus, comprising a reservoir having a tube therein for an antiseptic agent, 85 a spring actuated valve arranged to be connected with said apparatus to release a predetermined quantity of said agent when said apparatus is actuated, a second valve arranged to control said agent thus released, and means actuated by the water in said tank to effect the actuation of said second valve and thereby discharge of said agent into said tank.

3. A prophylactic device adapted to be used in connection with a toilet flush tank having flushing apparatus, comprising a reservoir arranged to contain a plurality of antiseptic pills or tablets, a valve arranged to be connected with said apparatus and actuated thereby to release said pills, and having means for selecting one or more of said pills to be released, and means arranged to arrest the pills thus released and arranged to be actuated by the water in said tank to 100 effect the discharge of said pills into the water in said tank.

4. A prophylactic device adapted to be used in connection with a toilet flush tank having flushing apparatus, comprising a 110 reservoir having a discharge outlet, a valve movable to open and close said discharge outlet and having means to convey the contents of said reservoir into said tank, means carried by said valve arranged to control the quantity of the discharge of said contents when said valve is actuated to open said outlet, a cage within said tank arranged to receive the contents of said reservoir as released by said valve, and means to prevent the discharge of said contents into said cage until the water has fallen in said tank below the lower end of said cage.

5. A prophylactic device adapted to be used in connection with a toilet flush tank having flushing apparatus, comprising a reservoir arranged to contain antiseptic pills and having a discharge outlet, a longitudinally movable spring-actuated valve connected with said apparatus and shifted 125 130

thereby to release a predetermined number of said pills, a conveyer tube for said pills leading into said tank, a valve at the discharge end of said conveyer tube, controlled by means comprising a float actuated by the rise and fall of the water level in said tank, and a cage arranged to receive said pills.

In witness whereof, I have hereunto set my hand this 4th day of May, A. D., 1916.

CONDY C. GALLAGHER.
